MASSAGE MACHINE

Robert H. Hassler, Old Westbury, N. Y., assignor
to Gro-Flex Corporation, Indianapolis, Ind., a
corporation of New York

Application July 29, 1933, Serial No. 682,739

3 Claims. (Cl. 128—46)

The invention relates to massage machines in which the massaging action is produced entirely by motive power, as distinguished from devices which are wholly or partly operated by hand. 5 While not necessarily restricted thereto, my improvements relate more particularly to machines for massaging and loosening the scalp of the human head.

Motor-driven massage machines offer certain 10 obvious advantages, such as elimination of labor, elimination of the attendant, if desired, and a massaging action which is at the same time more vigorous and more uniform. But for one reason or another there is a prejudice against motor-driven head-massaging machines and they have not come into extensive use. Disregarding devices which employ the vacuum principle and also shampooing appliances (these are not true massaging devices in the present sense), prior devices 15 have failed either because the massaging action was deficient in effectiveness or because of the liability of discomfort or even injury to the scalp or of snarling and tangling the hair. These defects are inherent in the prior devices, 20 in which a substantial movement is imparted to the applicator, relatively to the scalp, the motion being sometimes rotary and sometimes reciprocating.

With the aforementioned desiderata and 25 defects in view, it is the primary object of my invention to provide a motor-driven scalp massaging machine which will apply a vigorous and effective massaging action without causing pain to the user or entangling his hair.

More specifically, one object is to provide a 30 motor-driven massaging device which closely simulates the well-known and beneficial action of a skilled operator's fingers. This desired action is characterized by manipulation of the scalp upon the skull without appreciable rubbing or 35 dragging or pulling of the hair.

Another object is to facilitate the initial application of the device to the user's head and subsequent adjustments to vary the pressure of the 40 applicator and to permit application to various parts of the head. It is contemplated that an untrained user may easily apply the device and adjust it without interrupting the treatment. The device is thereby adapted for home use or it 45 may be employed in barber shops or beauty parlors with only general superintendence. It is believed that the user is better qualified than an attendant to determine the most effective adjustment.

50 Another object is to provide for the user's com-

fort during the treatment, not merely by eliminating the danger of pain and positive discomfort, but by relieving all strain and inducing a feeling of relaxation which materially increases the beneficial effects. 5

Another object is to enhance the commercial value and practicability of motor-driven massaging machines by improving their appearance, rendering them more reliable and durable in mechanical respects, and lowering the cost of 10 manufacture and maintenance.

In the accompanying drawings there is shown an illustrative embodiment of the invention which will now be described.

Figure 1 shows the invention, comprising a 15 chair and attached massaging unit, in side elevation, the massaging unit being lifted from the user's head.

Figure 2 is a similar view in which the unit is lowered into engagement with the user's head. 20

Figure 3 is a fragmentary central vertical section on a larger scale.

Figure 4 is a side elevation of the unit and its supporting bracket, broken away in parts.

Figure 5 is a bottom plan of the same, partly 25 broken away.

Figure 6 is a fragmentary bottom plan, like Figure 5, but with certain parts in changed positions.

Figure 7 is a transverse sectional view of the 30 applicator and associated parts, taken on the line 7—7 of Figure 4.

Figures 8 and 9 are similar views showing the parts in altered relations.

Figure 10 is a fragmentary view, partly in vertical section, of the members shown in Figures 7 to 9. 35

Figure 11 is a perspective view of the applicator, seen from above.

Figure 12 is a side elevation, partly in vertical 40 section, of the chair and height adjusting device.

Figure 13 is a transverse section on the line 13—13 of Figure 12.

Figure 14 is a rear elevation of the same members, partly broken away. 45

Figures 15 and 16 are fragmentary views of certain details of the height-adjusting mechanism.

Referring to the device generally, as shown in Figures 1 and 2, it comprises chair 1, supporting post 2, bracket 3, head rests 4, and massage unit 50 5 with its applicator 6.

Chair 1 may be of any suitable design. Preferably, it should be of the semi-reclining, upholstered type, conducing to the user's comfort during a treatment. Moreover, the back and sides 55

should be hollow and provided with framing suitably disposed to support the concealed operating parts hereinafter described. On the right side of the chair within easy reach of the user's hand is a switch 7, which is in circuit, through wiring concealed in the chair, with plug-in sockets 8 and 9 (Figure 14). One of these sockets may be connected to a source of electric current and the other to the motor contained in the massage unit and to be described later. The second socket is not indispensable but makes it possible to readily detach the massage unit from the chair, if desired.

Also within easy reach of the user when seated 15 is crank 10 by means of which he can raise or lower the massage unit. As shown in Figure 1, the unit is out of contact with the head and this is the correct position when the user seats himself and assumes a comfortable posture. He then 20 turns the crank to lower the applicator upon his head and throws switch 7 to start the motor. Guided by his sense of touch, the user may adjust the elevation of the applicator at any time without disturbing his position and without stopping 25 the motor. This enables the user to apply the applicator with the pressure best suited to his immediate requirements at any time during the treatment. He may relieve the pressure if it seems uncomfortably strong or may increase it 30 if a more vigorous massage is desired. Also, when tipping his head forward, backward, or sideways, to bring other parts of his scalp into range, the applicator may be raised or lowered to compensate for the changed position of the head.

35 Rotation of the crank 10 is transmitted as follows: The crank is journaled in frame member 11 and has a worm formed on its inner end which engages gear 12 on shaft 13. Bevel gear 14 on the lower end of shaft 13 is in mesh with bevel gear 40 15 on intermediate shaft 15^a on the other end of which is bevel gear 15^b in mesh with bevel gear 15^c on worm 16. Traversing nut 17 engages worm 16 and is seated in slotted follower 18 which is secured to post 2 near its lower end. The post is 45 aligned and guided by an elongated flanged channel 19 which is closed by cover plate 20 and bolted to frame member 21 (Figure 13). 22 is a finishing cap which is screwed to channel 19.

Bracket 3 has a slot 23 (Figure 5) which receives post 2 and the bracket is removably attached to the post by screws 24. The bracket is of channel form and terminates at its inner end in a yoke 25 which embraces and rigidly supports the message unit 5.

55 A pair of padded head rests 4 are positioned to engage the back of the head, affording a comfortable support and resistance to the tendency of the applicator to move the head. This is an important feature of the invention, because movement of the head with the applicator would be uncomfortable and fatiguing to the user and would materially diminish the massaging action, which depends upon manipulating the scalp while the skull remains substantially in fixed position.

60 Each head rest has a central socket 26 in which is seated a ball 27 formed on the end of a pin 28. This ball and socket joint permits the head rests to mutually and individually adjust themselves to the contours of heads of different shapes. Pins 29 project respectively from arms 29 of yoke 70 30 which is pivotally mounted on pin 31. Yoke 30 has a rearward extension 33 which coacts with stop 33^a to limit the upward movement of the arms 29 and head rests 4. A resilient cushion 34 is

confined between ledge 32 and bracket 3, so that the head is yieldingly supported.

The message unit will now be described. As previously stated, it is rigidly supported in yoke 25 of bracket 3. A body member 5 with cover 36 5 form a casing in which the motor and associated parts are housed. Body member 5 has an internal annular shelf 37 upon which are mounted bearings 38, 39 for the shaft 40 of motor 41. The motor may be of usual construction and need not be particularly described. Worm 42 on the right hand end of shaft 40 drives (through an intermediate gear and shaft which are not shown) gear 43 which is in mesh with a large internally toothed gear 44. Gear 44 and the applicator 10 which depends from it are supported as follows:

To hub 45, integral with shelf 37, is screwed plate 46 which projects beyond the hub to provide a ledge on which rests a ball bearing comprising an inner race 47 and outer race 48. The outer race has a flange 49 to which gear 44 is secured by screws 50. A second ball bearing, designated generally as 51, is interposed between the first-mentioned ball bearing and shelf 37.

Boss 52, formed on the under side of gear 44, 25 is eccentric and oblique to the axis of gear 44. Pintle 53 projects from boss 52 and carries inner rings 54, 55 of ball bearings whose outer rings 56, 57 are seated in axial recesses in applicator 30 holder 58.

The applicator 6, preferably made of soft rubber, is in the form of a cap or helmet, studded on its inner surface with flexible, preferably integral, fingers 59. A central hub or boss 60 has integral flexible flanges 61 which loosely engage 35 reverse-angled ring 62 outwardly and lugs 63 engage the ring inwardly. The applicator may be assembled with the unit by slipping the hub portion 60 over ring 62. Flexible flange 61 rests upon flange 64 of ring 62 when the machine is 40 not in use and is sufficiently rigid to support the weight of the applicator, but will readily deflect to permit removal of the applicator for the purpose of cleaning it or substituting another applicator.

45 When the motor is running, gear 44 rotates and eccentric pintle 53 revolves about the axis of gear 44. The movement of pintle 53 produces an annular rocking movement of holder 58 and applicator 6. The annular rocking movement of the applicator effects, through the flexible fingers 59, a massaging action which is known in the art and need not be particularly described.

Because of the ball bearings between the holder 58 and pintle 53, and because the applicator is 55 frictionally engaged by the user's head, the tendency of the applicator to rotate on its own axis is materially diminished. Nevertheless I have found by extensive experiments that some slow rotation or "crawling" of the applicator upon its axis and, consequently, upon the user's head, is inevitable unless auxiliary means are provided to wholly prevent it. This is a serious drawback because even slight rotation of the applicator tangles and pulls the hair. Although the annular rocking type of massaging action is less dangerous in this respect than a reciprocating motion, nevertheless any crawling of the applicator upon the user's head renders the device very objectionable for scalp massage. To eliminate 70 this defect I have provided means for positively holding the applicator holder against rotation without interfering with its annular rocking movement.

On each side of the applicator holder 58 75

(Figures 3 to 6) there is a depending lug 65 into which is tapped a screw 66. Upon the stem portions of the screws 66 are mounted bushings 67 which serve as journals for the perforated extremitiess 68 of a yoke 69. The yoke is secured to one end of a bar 70 whose other end is telescopically seated in a sleeve 71. Sleeve 71 is seated in a T 72 whose radial extensions 73 are bored to receive bushings 74. From each side a screw 10 75, having a threaded portion 76, is screwed into a threaded hole in the upper or lower side, respectively, of a rectangular ring or gimbel frame 77. Reduced smooth portion 78 of screw 75 is seated in bushing 74. The intermediate or lateral sides of frame 77 are also perforated to receive bushings 79 (Figure 5) into which project smooth portions 80 of screws 81. These screws have threaded portions 82 which engage correspondingly threaded holes in the sides of bracket 3. 20 The gimbel joint just described is protected by a shield 83 which has a hole 84 in which bar 70 rocks and reciprocates.

It will be seen that as applicator holder 58 revolves about the axis of gear 44, it will be held against rotation on its own axis but will be permitted to pass through all the phases of its annular rocking movement, since it can rock upon the axis of its pivotal connection with yoke 69 and also upon the axis of bar 70. Bar 70 will reciprocate in sleeve 71 as the applicator holder approaches and recedes from bracket 3.

In addition to the means described above for preventing the applicator holder from turning on its own axis, I have found it necessary to provide means for preventing the applicator from "crawling" relatively to the holder. It is not entirely clear just what causes this crawling action, but observation of numerous tests discloses the fact that even when the holder is positively held against rotation on its axis, the pad will rotate on the holder in the proportion of say 3 or 4 turns for every 100 massaging revolutions or oscillations. Whether this crawling action is caused by the reaction of the numerous rubber studs working against the unsymmetrical and irregular shape of the human skull, or otherwise, the fact remains that the phenomenon occurs in a degree sufficient to render a device of this character commercially unpractical in the absence of means for holding the applicator against crawling. To obviate this defect, I provide a series of lugs 62^a projecting radially inward from rings 62. Lugs 62^a coact with lugs 63 on the applicator (previously described) to prevent free rotation of the applicator relatively to the applicator holder except through a small arc. In the embodiment shown, this would be something in the neighborhood of 40°.

But while the arrangement which has been described effectively prevents the applicator from turning on its own axis, and tends to prevent the applicator from crawling on the holder, I deem it desirable to provide further against relative rotary movement between the applicator and the user's head, as when the head itself is turned, either inadvertently or purposely in shifting the position to bring different parts of the scalp into

the range of the applicator. Accordingly, the applicator is so mounted upon the holder as to permit the applicator to turn with the head in case of need, as when the head is suddenly twisted. If such a movement of the head occurs in the clockwise direction when the parts are in the position shown in Figure 7, lugs 63 will move out of contact with their corresponding lugs 62^a; but if the movement of the head is in the counter-clockwise direction, lugs 63, which are flexible and preferably of soft rubber integral with the applicator, will be deflected by lugs 62^a and slip over onto the opposite sides of the last-mentioned lugs. I have found it desirable to interpose anti-friction means between the applicator and the holder, as for example the anti-friction washers shown at 85.

It will be seen that in solving the problem of successful head massage, it has been necessary to reconcile two factors which are opposed to one another. On the one hand, it is necessary to prevent the applicator from crawling in response to the massaging action, but on the other hand the applicator must turn when the head turns. If it does not, tangling will result from this cause as well as from the crawling action previously referred to. By the means described, I have reconciled these conflicting factors and produced a head massaging machine in which there will be no substantial rotation of the applicator upon the head.

As a further shield for the moving parts and as a guard to prevent the user from accidentally thrusting his fingers between the rocking holder 58 and the rotating gear 44, I provide a collar 86, preferably of soft rubber, whose upper rim is in the form of a grooved bead 87 which can be slipped over flange 88 on casing 5.

I claim:—

1. A massaging machine comprising in combination, an applicator, means for annularly rocking said applicator, and means holding said applicator against rotation on its own axis, said holding means comprising an arm projecting radially from said applicator and hingedly connected to said applicator upon an axis perpendicular to the axis of said applicator, a keeper telescopically engaging said arm outwardly from said applicator, a fixed support, and a universal joint connecting said keeper to said fixed support.

2. A massaging machine comprising in combination, an applicator holder, means for annularly rocking said holder, an applicator carried by said holder, and means opposing the normal tendency of the applicator to rotate relatively to the holder but yieldable to an abnormal rotative force.

3. A massaging machine according to claim 2, in which the means for opposing rotation of the applicator relatively to the holder comprises interengaging lugs on said applicator and said holder respectively, the lugs on one of said members being deflectable by the lugs on the other member.

ROBERT H. HASSSLER.
